2 Sheets-Sheet 2

Fig. 5.

UNITED STATES PATENT OFFICE.

FRANK MASH, OF DETROIT, MICHIGAN.

MUSIC-LEAF TURNER.

Application filed March 15, 1920. Serial No. 365,396.

To all whom it may concern:

Be it known that I, FRANK MASH, a subject of the King of Italy, residing at Detroit, in the county of Wayne and State of Michigan, have invented certain new and useful Improvements in Music-Leaf Turners, of which the following is a specification, reference being had therein to the accompanying drawings.

10 This invention relates to a music leaf turning device and has special reference to that type of device which may be installed on a music rack, stand or other music leaf support, whether the same be of an organ, piano or other instrument.

15 The primary object of my invention is to provide a novel device by which leaves of a musical composition may be turned, one at a time, during the rendition of the composition, without the musician or others turning the sheets or pages of the composition by hand, thus permitting of entire attention being given to the music to be rendered and avoiding any momentary interruption.

20 Another object of my invention is to provide a music leaf turning device that will not injure the leaves or pages to be turned and which will not cause the sheet of music to become accidentally displaced due to any 25 turning operation.

25 A further object of my invention is to provide a music leaf turning device embodying spring actuated turning arms which are manually placed under tension and are 30 adapted to be released by a novel pawl and pin shaft releasing mechanism. The device also includes a restoring mechanism and a novel adjustable return member associated with the mechanism so that music 35 may be repeated when necessary.

40 A still further object of my invention is to provide a device of the above type wherein the parts are constructed with a view of reducing the cost of manufacture and at the 45 same time retain those features by which durability, ease of assembling and installation are secured. With such ends in view, my invention resides in the novel construction to be hereinafter considered and then 50 claimed, and reference will now be had to the drawings, wherein

55 Figure 1 is a front elevation of the music leaf turning device, partly broken away;

Fig. 2 is a horizontal sectional view, on an enlarged scale, taken on the line 2--2 of Fig. 1;

Fig. 3 is an enlarged cross sectional view of a portion of the device illustrating the arm restoring mechanism;

Fig. 4 is a perspective view of a portion 60 of one of the turning arms;

Fig. 5 is a rear elevation of the music leaf turning device;

Fig. 6 is a side elevation of a portion of the same illustrating the ratchet mecha- 65 nism;

Fig. 7 is a detail sectional view of a portion of the mechanism showing the pin shaft releasing mechanism;

Fig. 8 is a horizontal sectional view of the 70 main arbor or shaft of the device showing in plan one of the turning arms;

Fig. 9 is a longitudinal sectional view of a portion of one of the spring actuated 75 turning arms;

Fig. 10 is a perspective view of an adjustable return member;

Fig. 11 is a perspective view of an adjustable positioning and cushioning member;

Fig. 12 is an enlarged horizontal sectional 80 view of a portion of the device, showing the location of the return and cushioning members;

Fig. 13 is an enlarged elevation of the 85 same;

Fig. 14 is a perspective view of a portion of the leaf turning device, and

Fig. 15 is a horizontal sectional view of a portion of the leaf turning device.

In the drawings, 1 denotes an angle ledge 90 having a central upright 2 and said ledge and upright may form part of a rack, support or holder for sheets of music, a book, or leaves of a musical composition, so that same will be held within the vision of a 95 musician operating on an organ, piano or other instrument. The ledge 1 is adapted to support the lower edges of the leaves to be turned, in either direction, during the rendition of the musical composition, and at the 100 upright 2 is a resilient retaining member 3^a, adapted to engage in the central portion of a book or sheets of music and retain the same on the ledge 1 with the leaves or pages free to be turned in either direction. 105

3 denotes a depending shaft or arbor carried by the ledge 1 contiguous to the upright 2, and the lower end of said shaft or arbor is fixed in a horizontal support 4 forming part of a depending bracket 5 carried by 110 the ledge 1, at one side of the vertically disposed arbor.

- 6 denotes a plurality of superposed cup shaped spring holders non-rotatably mounted on the arbor 3 and between each one of these spring holders are the apertured heads 7 of turning arms 8, said arms being flat and disposed in parallelism with the outer ends thereof provided with leaf engaging members 9. These members are placed in engagement with the outer free edges of leaves 10 of music and are adapted to turn the leaves when the inner edges thereof are bound in a suitable binding or are held by the retaining member 34. The leaf engaging members 9 extend upwardly in notches 10 provided therefor in the ledge 1 and are adapted for turning a music leaf, without injury or displacement of the same.
- 11 denotes coiled springs in the spring holder 6, said springs having convolutions thereof disposed about the hub portion 12 of said holders and each spring has one of its end convolutions thereof anchored, as at 13, in the holder and the other end convolution anchored, as at 14, in the head 6 of the arm 8 on said holder, said head closing the holder and rotatable on the hub portion 12 thereof. The springs 11 are adapted to be placed under tension when the turning arms 8 are swung from the left to the right, considering Fig. 1, and when the arms are released from the right hand position thereof, the tension of the springs 11 is sufficient for swinging said arms from a right hand position to a left hand position.
- 15 denotes a side wall of the support 4 and connecting said side wall and the bracket 5 is a transverse pin 16 supporting a plurality of spring pressed pawls 17, said pawls being pressed and held normally elevated by spring 18 on the support 4. The pawls are adapted to temporarily hold the turning arms 8 at the right hand side of the music leaf turning device, with the springs 11 under tension, by engaging depending lugs 19 carried by the heads 7 of the turning arms 8, said pawls corresponding in number to the arms and the lugs 19 thereof. It is therefore possible to swing a turning arm from the left hand side of the device to the right hand side thereof and have it held in such position by a pawl, the lug 19 of the arm riding into engagement with the upper end 20 of the pawl to be temporarily held thereby.
- 21 denotes a rotatable pin shaft supported by the side wall and the bracket 5, said pin shaft having a plurality of beveled pins 22 positioned to successively engage the pawls 17, as best shown in Fig. 7. The pin shaft 21 is adapted to be intermittently moved to actuate two of the pawls 17 at one time, release the lugs 19 of the arms 8, and permit the springs 11 to turn said arms. The pins 22 are arranged in sets of two so that two of the pawls 17 will be actuated and

this is necessary so that there will be clearance for the lug 19 of the arm to be released. As the arms swing in substantially a horizontal plane the lugs 19 move in an arc and would strike adjacent lugs if said lugs were not moved out of the way. By observing Fig. 15 and the dot and dash lines indicating the remarks in which the lugs swing, it will be noted that it is necessary to depress two of the pawls at a time, otherwise a lug liberated by one pawl will impinge against an adjacent pawl, unless such adjacent pawl is lowered. When it is lowered, the lug released by it will be temporarily held by the next adjacent pawl, but when the second pawl is restored to normal position the second lug is moved back. This is true clear through to the last pawl, controlling the last arm, which is the only arm that may be swung back so that the last sheet of music may be repeated.

23 denotes a ratchet wheel mounted on the pin shaft 21 at the outer side of the wall 15 and normally engaging said ratchet wheel is a spring 24 to prevent a clockwise rotation thereof. (See Fig. 6). The ratchet wheel 23 is also engaged by a spring projected dog 25 reciprocable in a yoke 26 pivoted on the side wall 15, said dog extending through a guide 27 of the wall 15, so that it cannot become laterally displaced. The free end of the yoke 26 is held normally elevated by a spring 28 carried by the wall 15, and pivotally connected to the free end of the yoke is a hanger 29 by which the free end of the yoke may be lowered and cause the dog 25 thereof to impart movement in a counter-clockwise direction to the ratchet wheel 23, thereby rotating the pin shaft 21 and causing certain pawls 17 to be actuated. The elements 23 to 29 inclusive constitute a ratchet mechanism for imparting movement to the pin shaft 21, and this ratchet mechanism may be considered as part of an arm releasing mechanism to be hereinafter considered.

30 denotes a guide at the upper end of the bracket 5 and slideable in said guide and on a portion thereof is a horizontally disposed rack 31, said rack having a portion thereof slotted, as at 32, to receive the fork 33 of a bell crank 34 pivoted, as at 35, on the lower end of the bracket 5. The rack 31 is held normally retracted by a coiled spring 36 and said rack is adapted to be shifted by the bell crank 34, said bell crank being connected to a cable, rod, or actuating member 37, which is adapted to extend to a point convenient to a musician, so that the musician may quickly use his hands or foot to operate the member 37.

38 denotes a pinion loose on the upper end of the arbor 3 and the lower face of said pinion has an adjustable return member 39 adapted to be positioned to engage upwardly

extending lugs 40, carried by the turning arms 8, adjacent the heads 7 thereof. This returning member can be shifted, so that it will return either of the turning arms 8 from the 5 left side of the device to the right side thereof, when it is desired to repeat part of the music. It is now apparent that the actuating member 37 may be pulled upon to swing the bell crank 34, shift the rack 31 and swing 10 the adjustable return member 39, so that a turning arm will be swung to the right, still considering Fig. 1, and thus permit of music being repeated. As the pins 22 of the shaft 21 may not be in position for holding the 15 returned arm, I have provided an auxiliary lock for temporarily retaining the returned arms during the rendition of the music.

41 denotes a guide on the outer side of the bracket 5 and slidable in said guide is an 20 angular detent 42 adapted to have its upper end engage the rear end of the rack 31 and hold said rack in an extended position. The lower end of the detent 42 is connected by a transverse bar 43 to the hanger 29 and 25 said transverse bar is connected by a coiled retractile spring 44 to the support 4 with the retractile force of said spring holding the bar 43 normally elevated and the upper end of the detent 42 against the lower face 30 of the rack 31, as shown in Fig. 3, so that the detent may immediately engage behind the rack when it is extended. A cable or suitable actuating member 45 is connected to the transverse bar 43 and this actuating 35 member also extends to a point convenient to the musician, so that it may be pulled upon to release the arm retained at the right hand side of the device, whether it be an arm that is to turn a sheet of music for the first time 40 or a second time as would be the case after repeating a portion of the musical score.

46 denotes an adjustable positioning and cushioning member slidably supported in an 45 opening of a radially disposed holder 43^a, on the arbor 3 and normally held in an extended position by a coiled retractile spring 47 connected to one end of said member and to an arm 48 extending outwardly from the arbor 3. The opposite end of the member has a 50 cam or beveled portion 49 into engagement with which the lugs 40 ride when the arms 8 are swung from the right to the left, and with the lugs 40 engaging the cam 49, said lugs are supported slightly in advance of one 55 another, thus separating the members 9 of the arms 8 to a certain extent, and this separation is the result of the arms being cushioned when assuming a left hand position. For instance, the springs 11 will 60 forcibly swing the arms from right to left and when the lugs 40 engage the cam 49 of the adjustable arm positioning member 46, said member will be shifted against the action of the spring 47 and cushion the turning movement of the arms 8 just before reaching the 65 limit of their travel from right to left. Such a cushioning or arm positioning member is not necessary for the turning arms when assuming a right hand position, but it prevents slamming and throwing of the arms 70 in assuming a left hand position. The member 43 also serves another purpose. It has a notch 46 and extending into said notch is a projecting portion or lug 39^a of the return member 39, so that as the arms 8 shift 75 the member 46 said member will shift the return member 39, and position said return member so that its lug 39^a will be behind the last arm 8,—swung from right to left—and thus permit of the last arm and its music 80 sheet being turned back for a repetition of that portion of the music.

Considering the operation of the device and assuming that the members 9 have been placed in engagement with the lower edges 85 of sheets of music, at the free edges or sides thereof, all of the turning arms 8 are swung to a right hand position and the arms so retained by their respective pawls 17. Now, when the actuating member 45 is pulled 90 upon, the ratchet mechanism is actuated to impart movement to the pin shaft releasing mechanism and the turning arm attached to the first sheet of music is released, permitting of said sheet being swung from the 95 right to the left. After all the sheets have been turned from right to left, only the last sheet can be turned back for repeating purposes, and this is accomplished by pulling on the actuating member 37 when the 100 arm restoring mechanism will be actuated to swing the last swinging arm back to its original position, to be temporarily held until the actuating member 45 is again pulled upon to release the returned arm which is 105 held by the detent 42. After a turned arm has been re-turned, a pull upon the member 45 to release the re-turned arm will not cause other arms to be released and two sheets turned at one time, because of the 110 manner in which the arms are held as shown in Fig. 14, where it will be noted that the member 43 is spring retracted so that it may at all times engage one of the lugs 40 and permit of only one arm being turned at a 115 time.

With all of the lugs 40 closely assembled it is obvious that the return member 39 may, by engaging the lug 40 of the lowermost arm 8, restore all the arms to a right hand 120 position, this being necessary when there is to be a second rendition of the entire musical composition.

It is thought that the operation and utility of my device will be apparent without 125 further description and while in the drawing there is illustrated a preferred embodiment of my invention, it is to be understood that the structural elements are susceptible to such changes in size, shape and manner of 130

assemblage as fall within the scope of the appended claims.

What I claim is:—

1. In a music leaf turning device, the combination with a ledge, of an arbor carried thereby, a plurality of spring actuated turning arms carried by said arbor and adapted to be actuated by the springs thereof in one direction, means movably supported from said arbor adapted to cushion movement of said arms, and a restoring mechanism for said arms set by said movable cushioning means and adapted to individually or collectively restore said arms to the original position after having been actuated by the springs thereof.

2. A music leaf turning device as characterized in claim 1, wherein the restoring mechanism includes a rack and pinion and an adjustable return member carried by the pinion.

3. A music leaf turning device comprising a ledge, an arbor carried thereby, a bracket carried by said ledge, spring actuated turning arms supported by said arbor and adapted to be swung from one end of said ledge to the opposite end thereof, means including a rack and pinion for restoring any one of said arms to its original position,

and a slideable spring elevated detent associated with said rack and pinion adapted to engage behind said rack and hold either of said arms at a returned original position.

4. A music leaf turning device as characterized in claim 3, wherein said arbor supports means for cushioning a turning movement of said arms.

5. In a music leaf turning device, the combination with arms, and means for swinging said arms, of a cushion member adapted to be engaged by said arms and shifted thereby, a member adapted to be shifted by said cushion member, into position for turning the last arm to engage said cushion member, and means for turning said member.

6. The combination set forth in claim 5, wherein said cushion and turning members are disposed to move together during turning of the arms in one direction, and said turning member move independent of said cushion member during turning of the arm in the opposite direction.

In testimony whereof I affix my signature in the presence of two witnesses.

FRANK MASH.
